UNITED STATES PATENT OFFICE.

MATTHEW THIMGAN, OF MURDOCK, NEBRASKA.

DESIGN FOR A ROAD MARKER.

Application filed May 11, 1926. Serial No. 17,656. Term of patent 7 years.

To all whom it may concern:

Be it known that I, MATTHEW THIMGAN, a citizen of the United States, residing at Murdock, in the county of Cass and State of Nebraska, have invented a new, original, and ornamental Design for a Road Marker, of which the following is a specification, reference being had to the drawings, forming part thereof.

In the drawings,

I claim:

The ornamental design for a road marker, as shown.

MATTHEW THIMGAN.
